USPC D24/107, 158–160, 185, 186, 183, 184,
D24/137, 138

CPC G01N 2223/1016; G01N 2223/301; G01N

FIG. 1 is a front perspective view of a first embodiment of our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and

FIG. 7 is a left side elevational view thereof;

FIG. 8 is a front perspective view of a second embodiment of our new design;

FIG. 9 is a front elevational view thereof;

FIG. 10 is a rear elevational view thereof;

FIG. 11 is a top plan view thereof;

FIG. 12 is a bottom plan view thereof;

(Continued)

FIG. 13 is a right side elevational view thereof; and,
FIG. 14 is a left side elevational view thereof.
